CONTROL SYSTEM

Heber L. Newell, Bridgeport, Conn., assignor to
 General Electric Company, a corporation of
 New York

Application May 18, 1944, Serial No. 536,132

3 Claims. (Cl. 219—20)

This invention relates to control systems, more particularly to control systems for heating elements, such as the two heating elements of a twin unit hotplate, and it has for its object the provision of an improved control system of this character for limiting the maximum energy permitted to be consumed by the two elements, and also such a system which is quite flexible in its operation.

More specifically, this invention contemplates an improved control system for a pair of energy consuming elements, such as the heating elements of the above-mentioned hotplate, so that the elements cannot be simultaneously energized, but only alternately; and further, so that either one of the elements can be energized from zero per cent to 100 per cent of a measured time interval, while the other can be energized only for the complementary portion remaining of this time interval. And in addition, so that this other element can be energized from zero per cent to 100 per cent of its complementary portion of the time interval that remains.

For a more complete understanding of this invention, reference should be had to the accompanying drawings in which Fig. 1 is a front elevation of an electric stove provided with two heating elements and control means therefor embodying this invention, portions being broken away and shown in section so as to illustrate certain details of construction; Fig. 2 is a plan view of the electric stove shown in Fig. 1, parts being broken away and parts removed so that certain details of construction may be more readily viewed; Fig. 3 is a sectional view taken through the line 3—3 of Fig. 2 and looking in the direction of the arrows, this figure being drawn to a larger scale than Figs. 1 and 2; Fig. 4 is a plan view of a portion of the mechanism shown in Fig. 3; Fig. 5 is a view similar to Fig. 4 but illustrating the elements in different operative positions than they occupy in Fig. 4; and Fig. 6 is a perspective view illustrating certain of the control elements embodying this invention, and also illustrating diagrammatically the controlled heating elements.

Referring to the drawings, this invention has been shown in one form as applied to an electric stove 10 provided with a pair of heating elements 11 and 12. As shown, the stove 10 comprises a substantially rectangular casing 13 which at the four corners is provided with supporting legs 14. The two heating elements 11 and 12 are mounted in the top wall 15 of the casing, as clearly shown in Figs. 1 and 2. The heating elements are of similar construction, each comprising an insulat-

ing brick support 16 in which is formed a groove 17. Mounted in the two grooves 17 of the heating elements 11 and 12 are resistance conductors 18 and 19 respectively. Mounted within the forward part of the casing 13 are incandescent signal lamps 20 and 21 which are connected in parallel with the two heating elements 18 and 19 respectively, as shown in Fig. 6 and which therefore are energized when the heating elements are energized. These lamps are positioned back of windows 22 and 23 in the front wall of the casing so that their illumination may be seen.

Suitable control means are provided for the two heating elements whereby they cannot be simultaneously energized, but can only be alternately energized. Moreover, the control means operates on a time basis so that either one or the other of the heating elements can be energized from zero per cent to 100 per cent of a fixed measured time interval while the other unit can be energized for only the complementary portion that remains of the time interval. In other words, if the first element can be energized one-hundred per cent of the time interval, then the second element cannot be energized at all, but if the first element be energized for a fraction of the total time interval, then the second element may be energized for the fraction of time that remains. Furthermore, the control is so constructed and arranged that the second element can be energized from zero per cent to one-hundred per cent of the complementary portion of the time interval that remains.

The control means comprises a supporting shaft 24 which is mounted vertically within the casing 13. This shaft is mounted within a suitable bracket 25. The bracket 25 has a base 26 which rests upon and is secured to the bottom wall 27 of the casing 13. The bracket is also provided with a top member 28 which is parallel to the base 26, the base 26 and the top portion 28 mounting the shaft 24. Secured to the top of the shaft is a collar 28a which functions as a thrust bearing for the shaft.

Mounted upon and to oscillate about the shaft 24 is a movable contact member 30. The contact member 30 comprises an electrically conducting arm 31 which at its two ends carries on its opposite sides contacts 32 and 33. The contact member 30 has in general a T-shape, and as shown, the post 34 of this member is rigidly secured to an electrically insulating member 35. This member 35 in turn is mounted to oscillate on the shaft 24.

The support 35 and hence the contact mem-

ber 30 is periodically oscillated through a fixed path. This is accomplished by means of a suitable constant speed timing motor 36 of any suitable well-known construction, which motor drives a crank 37 which is mechanically interconnected with the support 35 by means of a link 38. The motor 36 is energized from a suitable electrical source of supply 39, and as it continuously operates it oscillates the contact member 30 through its fixed path of motion.

Cooperating with the two oscillating contacts 32 and 33 respectively are contacts 40 and 41. The contact 40 is mounted upon an electrically conducting strip 42 which in turn is secured to an electrically insulating block 43; this block is freely rotatable on the shaft 24. In a similar way the contact 41 is secured to an electrically conducting strip 44 which is secured to an insulating block 45 which also is freely rotatable on the shaft 24. The supports 35, 43 and 45 are separated by spacers 45a and 45b mounted upon the shaft 24.

As shown diagrammatically in Fig. 6, the contacts 32 and 40 control the energization of the heating element 18 and its lamp 20 so that when the contacts are closed both the heater and the lamp are energized, whereas when they are open both the heater and lamp are deenergized. In a similar way the contacts 33 and 41 control the energization and deenergization of the heating element 19 and its associated signal lamp 21.

Controlling the coaction between the contacts 32 and 40 and the contacts 33 and 41 respectively are suitable control levers 46 and 47 which are mounted upon the vertical shaft 24 for free rotation with reference to it, and which are properly spaced by spacers 45c and 45d. As shown, the two levers 46 and 47 are provided with U-shaped end sections 46a and 47a which are journaled on the shaft 24. Interposed between the two arms of these U-shaped members are compression springs 46b and 47b which bias the upper arm of the upper U against the under surface of the member 28 and the lower arm of the lower U against the top surface of the bottom wall 27. This is for the purpose of holding the levers 46 and 47 in their adjusted positions by the frictional forces between the co-operating surfaces. Interposed between the lever 46 and support 43 is a tension spring 48, while a similar spring 49 is interposed between the support 45 and the lever 47. These two tension springs bias the contact 40 toward the contact 32 and the contact 41 toward the contact 33. In other words, as the contact member 30 oscillates to oscillate its contacts 32 and 33, the contacts 40 and 41 tend to follow these two oscillating contacts respectively. However, the levers 46 and 47 control the motions of the contacts 40 and 41 so that only one at a time can energize its associated contact 40 or 41 whereby only one of the heaters 18 or 19 can be energized at a time. This is accomplished by means of stops 50 and 51 provided on the levers 46 and 47 respectively and which are arranged to engage adjustable abutments 52 and 53 mounted on the supports 43 and 45 respectively. The adjustments of the levers 46 and 47 and hence of their stops 50 and 51 control the extent of movement of their associated contacts 40 and 41 in following the movable contacts 32 and 33.

The position of the lever 46 is adjusted by means of a control lever 54 pivotally mounted on the bottom wall 27 of the casing, which lever is connected with the lever 46 by means of a

link 55. In a similar way the position of the lever 47 is controlled by a lever 56 which is connected to the lever 47 by a link 57. The two levers 54 and 56 extend through slots 58 and 59 respectively provided for them in the front wall of the casing 13, and on the exterior of the casing they are provided with knobs 60 and 61 whereby the levers may be conveniently operated.

It will be observed in view of the foregoing that when either of the levers 54, 56 is adjusted in its slot it will adjust the position of the associated lever 46, 47, and hence will adjust the position of the corresponding stop 50, 51. If the stop 50 be in its adjusted position shown in Fig. 6, then the contact 40 is in engagement with and is permitted to follow the movement of the contact 32 throughout its complete path of motion, whereby the heating element 18 is continuously energized throughout the complete stroke of the contact 32; and therefore for 100 per cent of the measured time interval. On the other hand, if the stop 51 is in its position shown in Fig. 6 it holds the contact 41 in such a position that it will not engage the contact 33 at any time during the complete oscillatory motion of the latter contact, whereby the heating element 19 remains completely deenergized throughout the measured time interval. Now if the stop 50 be moved counter-clockwise (Fig. 6) toward the associated abutment 52, then at some point in the oscillation of the contact 32 the motion of the contact 40 will be stopped and hence the element 18 de-energized. The proportion of time that the element 18 is energized to the time that it is de-energized, of course will depend upon the position of the stop 50. Also, if the lever 56 be adjusted to move the stop 51 clockwise (Fig. 6), then the contact 41 will move toward the contact 33 and eventually will engage it for some portion of its stroke so as to energize the heater 19 throughout this portion; throughout the remaining portion of the stroke of the contact 33 the contact 41 will be out of engagement therewith and the element 19 will be deenergized throughout this portion. In this way, the two heating elements 18 and 19 are alternately energized, and by adjusting the positions of the knobs 60 and 61, the percentages of time that they are energized are varied. When the knobs 60 and 61 are in their inner positions with reference to their slots 58 and 59, as shown in Fig. 2 in dotted lines in the case of the knob 60, and in solid lines in the case of the knob 61, then both elements 18 and 19 are completely deenergized throughout the full stroke of the contact member 31. By moving the knobs 60 and 61 outwardly from these inner positions, the percentages of time that the elements are energized are increased.

However, the two control levers 54 and 56 are mechanically interlocked so that when one of the heaters 18, 19 is energized for a portion of the period of movement of the oscillating contact member 31, the other can be energized only for the complementary portion remaining of the period, but this other heater element can be energized for any portion of this remaining complementary portion from zero per cent to 100 per cent thereof.

In the specific example illustrated, this interlock comprises a rigid rod 62 which is mounted in bearing members 63 and 64 rotatably mounted upon the two lever arms 54 and 56, respectively; the rod is freely slidable through the members 63 and 64. On one end of the rod 62 at the 75 left of the bearing member 63, as viewed in Fig.

3, is a cotter pin 65, while at the other end of the rod outside of the bearing member 64 are suitable adjustable nuts 66, the cotter pin and the nuts acting as stops cooperable with the bearing members 63 and 64.

It will be observed in view of the foregoing interlock arrangement that both of the levers 54 and 56 can be freely moved to their inner or "off" positions at the same time, but that only one of these levers at a time can be moved to its extreme outer or high heat position. (In Fig. 2 the solid line position of the lever 54 is its high heat position, while the solid line position of lever 56 is its "off" position.) If the lever 54 be moved toward its low heat position to some intermediate position, then it is obvious that the lever 56 is freed to be moved toward the right toward its high heat position to some intermediate position. Furthermore, it will be observed that if the lever 54 is in the aforementioned intermediate position, the lever 56 can be moved from its "off" position to any position between the "off" position and its aforesaid intermediate position, which intermediate position is always complementary to the position of the lever 54 in the sense of the extent of movement that it is permitted to go. In this way, while either heater 18 or 19 can be energized from zero per cent to 100 per cent of the time of one complete oscillation of the member 30, the other heater can be energized only for the complementary remaining portion of this interval of time. However, this other heater can be energized through the complete range from zero per cent to 100 per cent of this complementary portion of time.

While I have shown a particular embodiment of my invention, it will be understood of course that I do not wish to be limited thereto since many modifications may be made, and I therefore contemplate by the appended claims to cover any such modifications as fall within the true spirit and scope of my invention.

What I claim as new and desire to secure by Letters Patent of the United States is:

1. A heating system comprising a pair of heating elements, time element switching means for measuring a predetermined time interval and constructed and arranged to be operated alternately to energize said heating elements, separate control elements for said heating elements for selectively controlling said switching means, each movable through a predetermined range of motion from an "off" position to a high heat position, for effecting the energization of its controlled heating element from zero per cent to 100 per cent energization of said time interval, and flexible interlock means interconnecting said control elements constructed and arranged so that either one of said control elements can be moved without interference from the other from its "off" position to its said high heat position to energize its associated heating element to any degree from zero per cent to 100 per cent of said time interval, while the extent of movement of the other of

said control elements from its "off" position is limited to a maximum heat position wherein its associated heating element is energized only for the complementary portion remaining of said time interval, said flexible interlocking means, however, providing for unrestricted movement of said other heat control element to any intermediate heat position between said "off" and maximum heat positions to energize its associated heating element for any degree of energization from zero per cent to 100 per cent of said complementary portion.

2. A heating system comprising a pair of heating elements, a time element switching mechanism for controlling the energization of said heating elements provided with a first pair of control contacts reciprocating back and forth in unison in a predetermined timed interval, a second pair of contacts cooperating with said first pair respectively so as to control the energization of said heating elements respectively, means biasing said second pair toward engagement with said first pair so that they can move with said first pair in engagement therewith, adjustable stops for limiting the movement of said second pair of contacts in order to determine the proportion of said time interval said heating elements are energized respectively, interlocking means between said stops for controlling their relative adjustments so that one heating element can be energized for only the complementary portion remaining of said time interval that the other is energized, said interlocking means however providing for relative adjustment of the stops so that said one heating element can be energized from zero per cent to 100 per cent of said complementary portion.

3. A heating system comprising a pair of heating elements, a switch member mounted for oscillating motion having a pair of opposed contacts thereon, means for oscillating said member through a determined path, a second pair of contacts for cooperating with said first pair of contacts respectively, the two sets of paired contacts controlling the energization of said two heating elements respectively, means biasing said second pair toward the respective contacts of said first pair so that they tend to oscillate with said first pair and when either set is in engagement the associated heating element is energized, a pair of stops operably associated with said second pair of contacts respectively to control the extent of movement that the second contacts are in engagement with their oscillating contacts respectively, and an interlock between said stops controlling them so that only one of said sets of contacts can be closed at a time, and said one set can be closed from zero per cent to 100 per cent of the motion of said oscillating switch member, while the other set can be closed from zero per cent to 100 per cent of the complementary portion of said motion remaining.

HEBER L. NEWELL.
